(57) **CLAIM**

The ornamental design for a candle holder, as shown and described.

DESCRIPTION

FIG. 1 is a perspective view of a candle holder showing my new design;

FIG. 2 is front elevational view thereof, rear and side views being identical thereto;

FIG. 3 is a top plan view thereof;

FIG. 4 is a bottom plan view thereof, which includes dashed lines that are for purposes of illustration only and are not part of the claimed design.

FIG. 5 is a perspective view of an alternative embodiment of the candle holder;

FIG. 6 is front elevational view of FIG. 5; and,

FIG. 7 is a bottom plan view of FIG. 5.
